UNITED STATES PATENT OFFICE.

WILLIAM F. HODSON, OF HOUSATONIC, MASSACHUSETTS, ASSIGNOR TO MONUMENT MILLS, OF HOUSATONIC, MASSACHUSETTS, A CORPORATION OF MASSACHUSETTS.

DESIGN FOR A BEDSPREAD.

Application filed September 22, 1924. Serial No. 10,873. Term of patent 14 years.

To all whom it may concern:

Be it known that I, WILLIAM F. HODSON, a subject of Great Britain, residing at Housatonic, county of Berkshire, and State of Massachusetts, have invented a new, original, and ornamental Design for Bedspreads, of which the following is a specification, reference being had to the accompanying drawing, forming a part hereof.

The figure is a plan view showing a portion of a bedspread embodying my design. The design illustrated in the upper left hand corner of the bedspread is repeated in each of the other corners.

I claim:

The ornamental design for a bedspread, as shown.

WILLIAM F. HODSON.
